CLAIM

The ornamental design for a handle, as shown and described.

DESCRIPTION

FIG. 1 is a front, top, right side axonometric view of a handle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, left side axonometric view thereof; and,

FIG. 9 is a front axonometric view of the handle of FIG. 1, shown in a state of use with additional environmental subject matter.

The Dot-Dot-Dash broken lines seen in the drawings represent unclaimed environment and form no part of the claimed design. All other broken lines seen in the drawings depict portions of the handle that form no part of the claimed design.
